ARROW FLETCHING CLAMP

Henry A. Bitzenburger, 8920 Arrington Ave.,
Downey, Calif.

Filed Mar. 31, 1964, Ser. No. 79,287

Term of patent 14 years

(Cl. D54—13)

FIG-1

FIG-2

FIG-3

FIG-4

FIG-5

FIGURE 1 is a perspective view, taken from above, of an arrow fletching clamp, showing my new design;

FIGURE 2 is a perspective view thereof, taken from below;

FIGURE 3 is a rear elevational view thereof;

FIGURE 4 is a front elevational view thereof; and

FIGURE 5 is an end elevational view of the arrow fletching clamp.

I claim:

The ornamental design for an arrow fletching clamp, substantially as shown.
